UNITED STATES PATENT OFFICE

MAX L. WATERMAN, OF FAIRFIELD, CONNECTICUT, ASSIGNOR TO THE SINGER MANUFACTURING COMPANY, OF ELIZABETH, NEW JERSEY, A CORPORATION OF NEW JERSEY

FEEDING MECHANISM FOR SEWING MACHINES

Application filed April 9, 1931. Serial No. 528,794.

This invention relates to improvements in work-feeding mechanisms for sewing machines and more particularly in upper four-motion mechanisms of this character in which a work-advancing feeding-foot and a work-holding presser-foot are vertically reciprocated to alternately engage the work.

In upper four-motion feeding mechanisms of the character commonly known as the alternating-presser type, there is employed an automatic presser and feeding-foot lifting mechanism which is normally dependent upon the resistance imposed by the work or its support to the downward movement of either the presser-foot or feeding-foot in order to provide a fulcrum for lifting the other of said members. Obviously, if any cramping or inertia of the parts occasions a sufficient resistance before either of said members 15 in its descending movement reaches the work, the necessary fulcrum will be untimely provided and neither of said members will engage the work with the requisite pressure to insure advancing the work the necessary extent to effect the production of stitches of uniform length. The liability of imperfect operation of prior feeding mechanisms of this character increases with the speed of operation of the machine, due in a large measure 20 to inertia of the parts, and at high speeds a degree of inefficiency may be reached wherein neither the presser-foot nor the feeding-foot perceptibly engages the work.

The present invention therefore has for its primary object to improve the work-advancing efficiency of upper four-motion feeding mechanisms for sewing machines under operation at high speed and attains this object by the provision of feed-actuating mechanism 25 designed to insure alternate engagement of the work with the requisite pressure by the feeding-foot and the presser-foot.

In accomplishing the object of the invention, the feeding-foot and presser-foot are alternately raised above the work by mechanism designed to minimize cramping action of the presser-foot and feeding-foot carrying bars in their bearings, and the feeding-foot and presser-foot bars are individually subjected to spring pressure in a manner de-

signed to overcome inertia and also any frictional resistance to the free reciprocation of said bars.

The invention will best be understood from the following description of a preferred embodiment thereof illustrated in the accompanying drawings, in which Fig. 1 is a view in front end elevation of the bracket-arm head of a sewing machine having the improved feeding mechanism, the work-support and lower feed-dog being shown in section. Fig. 2 is an enlarged detail view, partly in section, of the needle- and feed-bars, illustrating the spring arrangement for depressing the feed-bar. Fig. 3 is a horizontal section of the front end of the machine bracket-arm substantially along the axis of the needle-actuating shaft journaled in said bracket-arm. Fig. 4 is a rear side elevation, partly in section, of the free end of the machine bracket-arm.

Referring to the drawings, the present improvements are shown as embodied in a commercially well known sewing machine having a work-support comprising a cloth-plate 1 and a throat-plate 2 provided with a feed-slot 3 in which operates a lower four-motion feed-dog 4 having a needle-aperture 5.

Overhanging the work-support is a bracket-arm 6 terminating at its free end in a head 7, in which bracket-arm is suitably journaled the rotary main shaft 8 carrying a crank-disk 9 connected in the usual manner by means of a link 10 with a collar 11 secured upon a needle-bar 12 carrying a needle 13. The needle-bar 12 is journaled for end-wise reciprocation in vertically alined apertures provided in bearing lugs 14 of a vibratory frame 15 which is pivotally supported at its upper end for jogging movements 17. The needle-bar 12 is journaled for end-wise reciprocation in vertically alined apertures provided in bearing lugs 14 of a vibratory frame 15 which is pivotally supported at its upper end for jogging movements 17. The needle-bar 12 is journaled for end-wise reciprocation in vertically alined apertures provided in bearing lugs 14 of a vibratory frame 15 which is pivotally supported at its upper end for jogging movements 17.

Any suitable means may be employed for jogging the frame 15 about the fulcrum-pin 16, the mechanism employed in the present machine for this purpose corresponding substantially with the rock-shaft and crank-arm 100

expedient disclosed, for instance, in the U. S. patent to J. C. Ringe, No. 1,685,436, Sept. 25, 1928. In Fig. 1 of the drawings herewith is shown in dotted lines the usual rock-shaft 5 18 having its crank-arm 19 operatively connected with the lower of the vibratory-frame bearing-lugs 14 for the purpose of jogging the frame.

The lower of the bearing-lugs 14 is also 10 provided with a vertically directed bore 20 slidably receiving a tubular feed-bar 21 upon the lower end of which is suitably secured the shank of a feeding-foot 22 preferably having a serrated work-engaging face. The 15 feeding-foot 22 is apertured to provide a passageway for the needle, and as both the needle-bar and the feed-bar are journaled in the vibratory frame 15, it is evident that the needle partakes of the work-advancing and return 20 movements of the feeding-foot, which latter and also the lower feed-dog serves to reinforce the needle against lateral stresses while in the work.

The feeding-foot is yieldingly urged toward the work-support by the action of a 25 coil-spring 23 interposed between the upper end of the feed-bar 21 and an abutment 24 in the present case integral with a guide-rod 25 embrased by the spring 23. The lower end of 30 the guide-rod 25 slidably enters the bore of the tubular feed-bar 21 and its upper end is guided by an apertured ear 26 projecting from the vibratory frame 15, whereby said 35 guide-rod 25 also partakes of the jogging movements of said frame. The rounded upper end of the guide-rod 25 is seated in the cupped end of an adjusting-screw 27 threaded 40 through the bracket-arm head of the machine frame and secured in adjusted position by means of a nut 28. The close proximity of the cupped end of the adjusting screw 27 to the fulcrum-pin 16 obviates any liability of unseating of the rod 25 during normal jogging 45 movements of the frame 15.

Projecting laterally from the headed upper 50 end of the feed-bar 21 is a stud 29 pivotally embrased by an apertured ear 30 at the lower end of a vertically directed link 31, of which the upper end has a stud 31' pivotally connected with an arm 32 of a two-armed lever 32, 33. The lever 32, 33 has intermediate its 55 ends a hub 34 apertured transversely of the length of the lever to receive a fulcrum-pin 35 projecting laterally from an arm 36 of a fulcrum-block 37 clamped by means of a screw 38 upon the usual presser-bar 39. The 60 presser-bar is vertically reciprocable in bushings 40 and 41 fixed in the machine bracket-arm head, said presser-bar being restrained 65 in the usual manner against turning in said bushings and carrying at its lower end a presser-foot 42 also preferably provided with a serrated work-engaging face. In the present case, the lever-arms 32 and 33 are in substantial alinement and are disposed substan-

tially normal to the vertical path of movement of the presser-bar.

The free end of the lever-arm 33 carries a stud 43 pivotally embrased by an apertured boss 44 upon the lower end of a bent link 45 of which the opposite end also carries an apertured boss 46. The link-boss 46 pivotally embrases a screw-stud 47 threaded into a crank-arm 48 upon one end of a horizontally disposed rock-shaft 49 journaled in bearing lugs 50 at the rear side of the machine bracket-arm, said rock-shaft 49 being substantially parallel with the main-shaft 8. Clamped upon the rock-shaft 49 by a screw 51 is the split hub of another crank-arm 52 pivotally connected with one end of a pitman 53 of which the opposite end has a strap 54 embracing an eccentric 55 suitably secured upon the main-shaft 8.

The presser-bar is as usual yieldingly depressed by a flat spring 56, disposed at the rear side of the machine bracket-arm and overlying a lug 57 of a split-collar 58 clamped upon the presser-bar by a screw 59. The fulcrum-block 37, previously referred to, has the usual lifter-arm 60 underlying which is the angular wear-plate 61 interposed between the lifter-arm 60 and a lifter-lever 62 pivotally secured by a screw 63 upon the rear side of the machine bracket-arm. A portion of the angular wear-plate 60 also underlies the arm 36 of said fulcrum-block 37 and is engagable by the usual hand lifter-lever 64.

In Fig. 1 of the drawings, the feeding-foot 22 is shown in its lowered position in engagement with the lower feed-dog 4 at substantially the beginning of the work-advancing movement of said feed-members, the presser-foot 42 being raised clear of the work-support. As the feed-members approach the end of their work-advancing movement, the rock-shaft 49 is actuated in a direction to lower the free end of the crank-arm 48 thereby swinging the lever 32, 33 about a fulcrum constituted by the pivot-stud 31' of the link 31. This swinging movement of the lever 32, 33, aided by the action of the spring 56 results in a downward movement of the presser-bar 39 which is arrested by the work-support or the work thereupon at substantially the completion of the work-advancing movement of the feeding-foot. The fulcrum of the lever 32, 33 is now automatically shifted from the pivot-stud 31' to the fulcrum-pin 35 and consequently the further downward movement of the link 45 rocks the lever 32, 33 about the fulcrum-pin 35, thereby lifting the feeding-foot 22 against the action of the spring 23, said feeding-foot while lifted clear of the work being returned to its forward position by the return jogging movement of the frame 15. The rock-shaft 49 is now oscillated in the opposite direction by the eccentric 55, thereby rocking the lever 32, 33 in the opposite direction about the fulcrum-pin 130

35 to effect a downward movement of the pivot-stud 31' and consequently lowering the feeding-foot 22 with the aid of the spring 23 into its initial position.

5 While it will be understood from the foregoing description that the present feeding mechanism resembles prior mechanisms of this character as to its general mode of operation, it will be observed that the alined

10 relationship of the lever-arms 32, 33 and the disposition thereof substantially perpendicular to the presser-bar 39 lessens considerably any effect to cramp the presser-bar in its bearings upon actuation of said lever.

15 Although the operating conditions are thus materially improved by the described mechanism for actuating the presser- and feed-bars, both the feeding-foot 22 and the presser-foot 42 fail to properly perform their func-

20 tions of advancing the work and of holding the advanced work, when said feeding-foot and presser-foot do not engage the work with the requisite pressure. At high speed operation, the inertia of the presser- and feed-

25 bars together with any frictional resistance to their reciprocation retards the downward movements of said bars to such an extent that the presser-foot and feeding-foot barely engage the work and may in fact walk entirely

30 above the work. By providing the spring 23 to act downwardly upon the feed-bar independently of the presser-bar, the inertia tendencies are effectively overcome without materially affecting the pressure distribution

35 which may be determined by individual adjustment of the presser-bar and feed-bar springs. The requisite adjustment of the feed-bar spring 23 is obtained by the screw 27 threaded into the machine frame to af-

40 ford a rigid abutment for the spring and to provide for conveniently effecting the adjustment.

Having thus set forth the nature of the invention, what I claim herein is:—

45 1. The combination in a sewing machine having a frame including a work-support, a reciprocatory presser-foot carrying bar, a feeding-foot carrying bar mounted for endwise reciprocatory and laterally jogging work-feeding movements, means for reciprocally actuating said bars in directions toward and from said work-support, and springs reacting against said frame thrusting individually upon said presser-foot and

55 feeding-foot carrying bars to yieldingly urge said bars toward the work-support.

2. An upper feeding mechanism for sewing machines including, in combination, a work-support, an endwise reciprocatory

60 presser-foot carrying bar, a spring acting to yieldingly urge said presser-foot carrying bar in a direction toward the work-support, a feeding-foot carrying bar mounted for endwise reciprocatory and laterally jogging

65 work-feeding movements, a lever having piv-

otal connections with both of said bars, means for rocking said lever to reciprocally actuate said bars toward and from the work-support, and a spring acting upon the feeding-foot carrying bar and compressed by the movement of the feeding-foot carrying bar in a direction away from the work-support under the action of said lever.

3. The combination in a sewing machine having a frame including a work-support, a reciprocatory presser-foot carrying bar, a feeding-foot carrying bar mounted for endwise reciprocatory and laterally jogging work-feeding movements, a lever pivotally connected with both of said bars having its arms in substantial alinement and disposed substantially normal to the path of reciprocatory movement of said presser-foot carrying bar, means for rocking said lever to reciprocally actuate said bars toward and from the work-support, and springs thrusting individually upon said presser-foot carrying bar and feeding-foot carrying bar to yieldingly urge said bars toward the work-support.

4. The combination in a sewing machine having a frame including a work-support, a reciprocatory presser-foot carrying bar, a feeding-foot carrying bar, a jogging frame in which said feeding-foot carrying bar is journaled for endwise reciprocation, means for reciprocally actuating said bars in directions toward and from said work-support, springs reacting against the machine frame and thrusting individually upon said presser-foot carrying bar and feeding-foot carrying bar to yieldingly urge said bars toward the work-support, and means for supporting one of said springs upon said jogging frame for vibratory movements therewith.

5. An upper feeding mechanism for sewing machines including, in combination, a work-support, an endwise reciprocatory presser bar, a presser-foot carried by said presser-bar in directions toward and from the work-support, a tubular feed-bar, a feeding-foot carried by said feed-bar, a jogging frame in which said feed-bar is journaled for endwise reciprocation, a guide-rod slidingly entering the tubular feed-bar having an abutment, a spring interposed between the abutment of said rod and said feed-bar acting to urge the feed-bar in a direction toward the work-support, adjustable stationary means opposing the thrust of said guide-rod in a direction away from said feed-bar, and means for reciprocally actuating the presser-bar and feed-bar in directions toward and from said work-support.

In testimony whereof I have signed my name to this specification.

MAX L. WATERMAN.
